(57) **CLAIM**

The ornamental design for a tool cap, as shown and described.

DESCRIPTION

FIG. 1 is a perspective view of the tool cap showing the new design;

FIG. 2 is a top view of the tool cap;

FIG. 3 is a bottom view of the tool cap;

FIG. 4 is a front view of the tool cap;

FIG. 5 is a rear view of the tool cap;

FIG. 6 is a left side view of the tool cap;

FIG. 7 is a right side view of the tool cap; and,

FIG. 8 is a perspective view of the tool cap on a representative tool.

The broken lines illustrate portions of the tool cap that form no part of the claimed design.
